UNITED STATES PATENT OFFICE.

MORTEN BALTHAZAR RICHTER, OF COPENHAGEN, DENMARK.

THREE-CONDUCTOR PLUG.

1,302,471.

Specification of Letters Patent. Patented Apr. 29, 1919.

Original application filed October 16, 1915, Serial No. 56,302. Divided and this application filed October 17, 1918. Serial No. 258,655.

To all whom it may concern:

Be it known that I, MORTEN BALTHAZAR RICHTER, a subject of the King of Denmark, residing at Copenhagen, Denmark, have invented certain new and useful Improvements in Three-Conductor Plugs, of which the following is a full and clear specification, illustrated in the annexed drawings. The particular novel features are more fully

10 pointed out in the annexed claims.

The contact plugs used in telephone stations frequently have the disadvantage that their composite elements tend to get loosened in their relative positions through the repeated action of the contact springs of the jacks with which the plugs continually cooperate. I have already produced two-conductor plugs through pressing of celluloid in hot and plastic condition into the space between the outer tube shaped cover and the central conductor to overcome this difficulty. The present invention aims at producing three-conductor plugs in the same manner. In producing such plugs, which consist of 25 an inner central conductor and two concentric conductors surrounding the same and insulated from the same and insulated from each other, difficulties have been found, partly in maintaining the parts in the correct relative position during the introduction into the mold, in which they are placed during the pressing in of the insulating material, and partly in preventing the change of this correct position of the parts under 30 the influence of the side pressure exercised by the plastic celluloid or other insulating mass which is pressed in through a single hole in the side and which should flow between and surround the inner parts, completely 35 filling out all cavities. According to the present invention, this is attained by the two inner conductors being secured to an auxiliary metal piece preferably by using the same screw holes in the conductors which 40 are later on used for attaching the flexible cords to them. This metal piece, together with the three conductors of the plug, is placed in a mold securing the concentric position of the parts and supporting the same, 45 whereby the metal piece in question takes up the side pressure which is exerted by the plastic insulating material when it is pressed in through a hole in the outer conductor opposite to the metal piece.

50 The method of manufacturing this plug has been described and claimed in a co-

pending application, Serial #56,302, filed October 16, 1915 of which the present application is a division, claiming in particular the structure of this plug.

60 The invention will now be described by way of example with reference to the annexed drawing, in which—

Figure 1 shows a plug according to the invention, the outer cover of insulating material being shown in section;

Fig. 2 represents an axial longitudinal section through Fig. 1.

Fig. 3 a sectional view of the outer conductor,

Fig. 4 the inner concentric hollow conductor,

Fig. 5 a sectional view of the same,

Fig. 6 the central conductor partially in section,

Fig. 7 the knob forming the outermost part of the plug in section,

Fig. 8 a metal ring for taking up wear,

Fig. 9 the contact plug partly in section prior to the pressing in of insulating material, together with the devices used for keeping the various parts in the correct mutual position,

Fig. 10 the parts of the contact plug placed in a mold ready for pressing in of the plastic insulating material, one half of the mold being removed, and

Fig. 11 a piece of cord for use in connection with the plug.

The outer conductor consists of a tube-shaped cover *a*. It is provided with an excision *b* in the side and with a coarse internal screw thread *c* for screwing in of the cord *f* provided with a soft coating *d*, (Fig. 11), one metal core *e* of which is bent over 90 and thus gets into contact with the cover *a*. Furthermore, the cover *a* is provided with fine outer screw threads *g* (Figs. 1 and 3) on which a tube *h* of insulating material can be screwed against a shoulder *i*, and finally 95 100 105 110 115 opposite to the excision *b* a conical opening *j* is provided in the wall of the cover *a* through which the plastic insulating material is to be forced. The inner hollow conductor *k* has the shape shown in Figs. 4 and 5 and ends in a ring-shaped part meant for making contact with one of the contact springs of a jack. In the other end is found a screw threaded hole *m* for the fastening screw for one core *o* of the cord, and a hole *n* through which plastic insulating material can be pressed. The central conductor con-

sists of a pin *q*, (Fig. 6), which is provided with a screw hole *p* on the end of which pin *q* the knob *r*, shown in Fig. 7, can be screwed, which latter is adapted for making contact 5 with another contact spring of the jack, and a metal ring *t*, Fig. 8, is insulated from the parts *r* and *k* and serves for taking up the greater part of the wear to which otherwise the soft insulating material would be subject 10 by the contact spring of the jack when the plug is inserted and withdrawn.

When such a contact plug is to be assembled and filled with material, a small fiber ring *u* (Fig. 2), is inserted in the cover *a*, 15 and a fiber ring *v* is pushed over the conductor *k*, which is now introduced into the cover *a* from the left side. The pin *q* is now introduced into the conductor *k* from the right side, and the knob *r* is screwed on 20 subsequent to the ring *t* being applied, which ring *t* has one fiber ring *t'* and *t''* on each side. A metal piece *x* (Fig. 9), the surface of which is partly cylindrical and partly of the shown stepped shape is now applied 25 and the parts *k* and *q* are secured to the same by means of screws *y* which are screwed into the holes *n* and *p* which later on serve for receiving the fastening screws for the cores of the cord. In a screw hole 30 in the end of the part *x* a thumb screw *z* is threaded, which has a shoulder abutting against the end of the cover *a* and thereby keeps the piece *k* and the ring *v* firmly pressed against the left hand end of the 35 cover *a*. While this arrangement keeps the inner conductors exactly centered at one end, their other ends are centered by the position of the whole plug in the split two-part mold, one half of which is shown in 40 Fig. 10. The mold is made of metal and has a suitable cavity accommodating the entire device shown in Fig. 9, the two halves being kept together by bolts 1. The mold is further provided with a cavity 2 of the 45 shape shown, containing a piston 3 and insulating material 4 and terminating right opposite to the opening *j* in the cover *a*. When the parts of the plug are laid in and the mold is screwed together, a thumb screw 50 5 is screwed in, pressing the piece *r*, the fiber rings and the ring *t* firmly against the part *k* and the other parts and taking up part of the pressure exerted by the insulating mass which is afterward introduced under pressure. In order to make possible the 55 independent setting of the part *r*, provision is made in part *x* for sufficient play of screw *y*, a small free space being provided as shown at 6 in Fig. 9. When the parts are 60 put together in this manner, the whole mold 7 with contents is heated until the insulating material 4 has become soft and plastic, and through a strong pressure on the piston 3,

the insulating mass is driven in through the opening *j*, filling out all the spaces between the parts *r*, *a*, *x* and the mold 7. After cooling, the plug is taken out of the mold and the superfluous part of the insulating mass is cut off.

The cover is at the end provided with 70 small notches 8, Fig. 3, and the ring *t* is provided with similar notches 9, and it is an indication that the plug is completely filled, when the insulating material pressed in, appears in and fills out the notches in 75 question. The cord *f* can now be screwed in and the cores *o* and *s* are fastened by means of screws, whereupon the outer tube *h* of insulating material serving as a handle, is screwed on.

The plug shown is only to be considered as an example and various details can be altered without departing from the spirit of the invention.

Having thus fully described my invention, 85 I claim as new and desire to secure by Letters Patent:

1. A plug comprising an outer hollow conductor, an inner rigid concentric hollow conductor, having an inner terminal, a central rigid conductor in the said inner conductor also having an inner terminal and a unitary integral body of insulating material occupying the annular spaces between the conductors and between said inner 95 terminals.

2. A multiple conductor plug comprising a central conductor, a plurality of rigid concentric hollow conductors, spaced from the central conductor and from each other by 100 auxiliary insulating elements, and a main body of insulating material pressed, while in a plastic condition, into the cavities between the several conductors not occupied by auxiliary insulating elements, said insulating material forming an integral body 105 throughout the plug and uniting the several plug elements to form an integral rigid structure.

3. A multiple conductor plug comprising 110 a central conductor, a plurality of rigid concentric hollow conductors, tubular auxiliary insulating elements between the several conductors and near one end thereof, a main body of insulating material pressed, while 115 in a plastic condition, into the cavities between the several conductors not occupied by the tubular auxiliary insulating elements, said insulating material forming an integral body throughout the plug and uniting the 120 conductors, auxiliary insulating elements and insulating material into an integral structure, and an outer insulating handling sleeve.

MORTEN BALTHAZAR RICHTER.
